UNITED STATES PATENT OFFICE.

THOMAS B. ATTERBURY, OF PITTSBURG, PENNSYLVANIA.

DESIGN FOR A DISH-COVER.

SPECIFICATION forming part of Design No. 19,250, dated August 6, 1889.

Application filed July 2, 1889. Serial No. 316,341. Term of patent 7 years.

To all whom it may concern:

Be it known that I, THOMAS B. ATTERBURY, a citizen of the United States, residing at Pittsburg, in the county of Allegheny and State of Pennsylvania, have invented and produced a new and original Design for Dish-Covers; and I do hereby declare the following to be a full, clear, and exact description of the same, reference being had to the accompanying drawing, forming a part thereof.

In the drawing I have shown in perspective an elliptical dish-cover, in general form being oval or mound shaped and having on the top thereof and covering the greater portion of the same a configuration of a fox.

A indicates the main body of the cover, having the short longitudinal ribs or flutings a, which extend around the base of the same, the portion b above the border a having a

plain or roughened surface b, with the handle portion B ornamenting the same in the shape or configuration of a fox lying down and curled up, with the exception of the head, which stands erect.

What I claim is—

The design for a dish-cover, consisting of the mound-shaped portion II, having a series of short longitudinal ribs extending around its base, and the handle portion B, having the configuration of a fox in a lying-down position with the head erect, as herein described and shown.

In testimony whereof I affix my signature in presence of two witnesses.

THOMAS B. ATTERBURY.
